COMBINATION BATTERY CHARGER AND TOOTHBRUSH HOLDER OR SIMILAR ARTICLE

George H. Fitzsimonds, Trumbull, Conn., assignor to
General Electric Company, a corporation of New
York

Filed May 21, 1962, Ser. No. 70,211

Term of patent 14 years

(Cl. D4—3)

Fig. 1.

Fig. 2.

Fig. 3.

FIG. 1 is a front perspective view of a combination battery charger and toothbrush holder embodying my new design;

FIG. 2 is a top plan view thereof;

FIG. 3 is a bottom plan view thereof;

FIG. 4 is a front perspective view thereof; and

FIG. 5 is a rear and a bottom perspective view thereof.

I claim:

The ornamental design for a combination battery charger and toothbrush holder or similar article, substantially as shown.
